C. D. PLATT,
ELECTRIC CUT-OUT BOX,
APPLICATION FILED MAY 22, 1920.

1,396,876.

Patented Nov. 15, 1921.

UNITED STATES PATENT OFFICE.

CLARENCE D. PLATT, OF BRIDGEPORT, CONNECTICUT.

ELECTRIC-CUT-OUT BOX.

1,396,876.

Specification of Letters Patent.

Patented Nov. 15, 1921.

Application filed May 22, 1920. Serial No. 383,386.

To all whom it may concern:

Be it known that I, CLARENCE D. PLATT, a citizen of the United States of America, residing at Bridgeport, Connecticut, have 5 invented a new and useful Electric-Cut-Out Box, of which the following is a specification.

My invention relates particularly to a construction having a hinged cover, and has for 10 its main object the provision of a special hinge which can be economically made, and which affords a secure and durable connection between the cover and the body of the box.

15 Figure 1 is an end view of an inclosed switch construction embodying the improvements of my invention.

Fig. 2 is a perspective view of the box, part of the cover being broken away.

20 Fig. 3 is a perspective view of a fragment of one side of the box showing one step in the formation of a hinge.

Fig. 4 is a fragmentary sectional view showing the method of connecting the parts 25 of the hinge.

Fig. 5 is a similar view showing the completed hinge with the cover open.

Fig. 6 is a fragmentary sectional view showing the cover closed.

30 Fig. 7 is a horizontal sectional view showing one method of securing one of the hinged parts in place.

The box has a body portion 10 and a cover 11 suitably interfitting and inclosing a 35 switch 12 of any suitable type adapted to be operated by an external handle 13.

The hinge loop 14 projects outwardly from the side of the box and embraces a bar portion 15 carried by the cover and formed 40 by perforating the cover at 16 near the edge of the flange 17. The hinge loop is formed by shearing or cutting a strap in the form shown at 18 in Fig. 3 with a loop 14. The ends of the straps 18 are then inserted in the 45 openings 16 in the flange of the cover and each strap is then bent into the position shown in Fig. 5.

When the cover is closed, it will be seen that the upper end of the strap 18 is like-

wise inside of the flange 17 as shown in 50 Fig. 6 so that it is impossible to bend or pry open the loop 14 to release the hinge. I prefer to provide a flange 19 along the edge of the cover opposite the hinges as shown in Fig. 1. 55

Additional security may be provided by fastening the upper end of each strap 18 to the adjacent portions of the side of the box as by means of spot welding or by displacing the metal as shown at 20 and 21, or by 60 both displacing the metal and welding. In view of the fact that the bar 15 is interposed beneath the loop 14, it is obviously more important to prevent the strap 18 from being pulled outward than it is from being pushed 65 inward.

The preferable method of securing the end of the strap in the slot is shown in Fig. 7. It will be understood that the strap 18 is the same width as the opening from which it is 70 sheared and after the cover has been located on the strap, the end of the latter is forced back into the opening and the metal of the box adjacent to the strap is displaced toward the strap on the outside of the box and 75 the metal of the strap is displaced in the opposite direction inside of the box which causes the two opposite displaced sections to overlap and interlock and prevents outward movement of the strap. The edges of the 80 straps and box may also be spot welded together if desired. I have illustrated only one method of interlocking the edges of the strap 18 with the side of the box 10, but it will be understood that other methods may 85 be employed.

I claim:

1. In an electric cut out box, a metal box body member, and a metal cover member for said box body member, one of said members 90 having a pintle thereon, the other of said members having slits therein, and the metal between said slits displaced to form a hinge tongue loop for receiving said pintle and hinging the cover to the box body, the metal 95 on a part adjacent one of said slits being displaced and forced over the metal on the part opposite the other part and adjacent the

slit, whereby the hinge tongue will be rigidly secured and the disengagement of the box body and cover prevented.

2. In an electric cut out box, a metal box body, an integral tongue formed on said body, said tongue being bent to form an outwardly-extending hinge loop, and a metal cover for said box body having a slot there-

in for receiving said tongue, the edge of the cover adjacent said slot constituting a pintle 10 co-acting with said hinge loop for hinging said box body and cover together, the free end of said tongue being secured to said box body, whereby the tongue is prevented from being displaced from the box body.

CLARENCE D. PLATT.
